UNITED STATES PATENT OFFICE.

LESLIE P. GREEN, OF CHICAGO, ILLINOIS.

SCRAPER.

Application filed January 14, 1924. Serial No. 686,001.

To all whom it may concern:

Be it known that I, LESLIE P. GREEN, a citizen of the United States, and a resident of the city of Chicago, county of Cook, and 5 State of Illinois, have invented certain new and useful Improvements in Scrapers, of which the following is a specification.

My invention relates to improvements in scrapers, and more particularly to the type 10 of scraper known as drag scrapers, adapted and arranged to move material by being dragged to and fro thereover, the object of the invention being to provide a simple and efficient construction of this character 15 capable of a wide variety of uses.

Other objects will appear hereinafter.

The invention consists in the combinations and arrangements of parts hereinafter described and claimed.

20 The invention will be best understood by reference to the accompanying drawing forming a part of this specification, and in which

Fig. 1 is a perspective view of a scraper 25 embodying the invention;

Fig. 2, a side view of the same shown partially in section;

Fig. 3, a section taken on line 3—3 of Fig. 2, and

30 Fig. 4, a side view of the forward portion of a scraper embodying a modified form of construction.

The form of construction illustrated in Figs. 1, 2 and 3 comprises a scraper body 35 consisting of two divergent vertical side walls 5, converging to an apex at the rear where they are secured together and provided with rearwardly extending adjoining lips 6 to which the rear drag cable 7 is 40 attached as indicated. The upper portions of sides 5 are forwardly bevelled at the rear and a closure plate 8 secured over said forwardly bevelled edges to re-enforce and strengthen the construction at this point and 45 also to prevent the formation of an acute angle into which the material would tend to pack and stick. A forwardly and downwardly inclined guard plate 9 is also secured between the sides 5 at the rear apex so as 50 to cut the apex proper from the body of the scraper, thereby preventing the formation of an acute angled recess at this point and re-enforcing and stiffening the construction. The lower edges of the side walls 5 are 55 turned inwardly to form scraping blades 10 and the edges of these blades are re-enforced

by strips 11 as shown, the forward edges of the strips 11 and the blades 10 being extended somewhat beyond the body of the scraper to form the digging points 12 as 60 indicated. The upper forward portions 13 of the sides 5 are bent into parallel relation with each other to form vertically extending parallel guides or keel plates which tend to guide the scraper on a straight path during 65 operation and also strengthen and stiffen the construction. The usual branches 14 of the forward drag cable are adjustably secured to the forward edges of the guide plates 13 as shown. 70

A cover plate 15 is secured across the top of the scraper being supported on and bolted to cross bars 16 as shown. The cover plate 15 is materially less in area than the top of scraper body so as to leave open spaces 75 around the sides and the rear thereof to permit the escape of water through the top of the scraper when in operation. The side edges of the cover plate 15 are turned upwardly and flared outwardly to constitute 80 guard flanges as indicated.

By this arrangement a strong, durable and efficient construction is provided capable of a wide variety of uses. In operation, when the body of the scraper has become 85 filled with material the same tends to exert an upward tendency on the cover plate 15 and thus prevent any further digging or scraping action and thus preventing overloading of the scraper and useless expenditure of energy. When operated under water the openings around the side edges and rear of the cover plate permit of the ready escape of water through the top of the scraper and the consequent filling of 90 the body of the scraper with solid material to be moved. The guard flanges 17 tend to prevent the deposit of material on top of the cover plate and also stiffen the construction. When the scraper is moved to and fro 100 over the material to be moved in the usual manner by means of the cables 7 and 14, the scraper body will be filled with material during the forward movement and will then "ride upon" this material as long as the 105 forward movement is continued, and thus carry said material with it to the desired point of deposit. Then the motion of the scraper is reversed and the material deposited at the desired point in the usual 110 way.

In the modified form of construction illus-

trated in Fig. 4 the vertical guide or keel plates 13 have been omitted and dispensed with and the capacity of the scraper correspondingly diminished. Otherwise the 5 construction is the same as that already described.

While I have illustrated and described the preferred form of construction for carrying my invention into effect, this is capable of 10 variation and modification without departing from the spirit of the invention. I, therefore, do not wish to be limited to the precise details of construction set forth, but desire to avail myself of such variations and 15 modifications as come within the scope of the appended claims.

Having described my invention, what I claim as new and desire to secure by Letters Patent is:

- 20 1. A scraper comprising a scraping body open at the bottom and provided with sides and a cover plate, said sides being adapted and arranged to collect material and force it upwardly against the underside 25 of said cover plate to elevate the scraper when filled, there being openings in said cover plate to permit the escape of water through the top of said scraper, substantially as described.
- 30 2. A scraper comprising a scraping body open at the bottom and provided with divergent sides and a cover plate, said sides being adapted and arranged to collect material and force it upwardly against the underside 35 of said cover plate to elevate the scraper when filled, there being openings in said cover plate to permit the escape of water through the top of said scraper, substantially as described.
- 40 3. A scraper comprising a scraping body open at the bottom and provided with sides and a cover plate, said sides being adapted and arranged to collect material and force it upwardly against the underside of said 45 cover plate to elevate the scraper when filled, there being openings around the sides and rear of said cover plate to permit the escape of water from the top of said scraper, substantially as described.
- 50 4. A scraper comprising a body open at the bottom and provided with divergent sides having inwardly turned lower edges and a cover plate, said sides being adapted and arranged to collect material and force 55 it upwardly against the underside of said cover plate to elevate the scraper when filled, there being openings around the sides and rear of said cover plate to permit the

escape of water from the top of said scraper, substantially as described. 60

5. A scraper comprising a scraping body open at the bottom and provided with sides and a cover plate, said sides being adapted and arranged to collect material and force it upwardly against the underside of said cover plate to elevate the scraper when filled, there being openings around the sides and rear of said cover plate to permit the escape of water from the top of said scraper, and upwardly and outwardly flaring guards at the side edges of said cover plate, substantially as described. 65 70

6. A scraper comprising a body open at the bottom and provided with divergent sides having inwardly turned lower edges and a cover plate, said sides being adapted and arranged to collect material and force it upwardly against the underside of said cover plate to elevate the scraper when filled, there being openings around the sides and rear of said cover plate to permit the escape of water from the top of said scraper, and upwardly and outwardly flaring guards at the side edges of said cover plate, substantially as described. 75 80

7. A scraper comprising forwardly divergent sides; and a guard plate between said sides at the rear cutting off the apex of said sides from the body of the scraper, substantially as described. 85 90

8. A scraper comprising forwardly divergent sides having inwardly turned lower edges; and a guard plate between said sides at the rear cutting off the apex of said sides from the body of said scraper, substantially as described. 95

9. A scraper comprising a body open at the bottom and provided with divergent sides having inwardly turned lower edges, said lower edges extending forwardly well beyond the body of the scraper, and a cover plate, said sides being adapted and arranged to collect material and force it upwardly against the underside of said cover plate to elevate the scraper when filled, there being openings around the sides and rear edge of said cover plate; and upwardly and outwardly flaring guards at the side edges of said cover plate, substantially as described. 100 105

In testimony whereof I have signed my name to this specification in the presence of two subscribing witnesses.

LESLIE P. GREEN.
